UNITED STATES PATENT OFFICE.

WILLIAM C. MCKINNEY, OF TORONTO, ONTARIO, CANADA, ASSIGNOR TO STANDARD SANITARY MANUFACTURING COMPANY, OF PITTSBURGH, PENNSYLVANIA, A CORPORATION OF NEW JERSEY.

FOOT ATTACHMENT.

1,078,104.

Specification of Letters Patent.

Patented Nov. 11, 1913.

Application filed March 8, 1913. Serial No. 753,111.

To all whom it may concern:

Be it known that I, WILLIAM C. MCKINNEY, residing at Toronto, in the Province of Ontario, Dominion of Canada, a citizen 5 of the United States, have invented or discovered certain new and useful Improvements in Foot Attachments, of which improvements the following is a specification.

My invention relates to cast metal articles provided with detachable feet, and has 10 to do particularly with the manner of attaching feet or similar supporting members to bath tubs, foot-tubs and like sanitary articles formed of cast metal and provided 15 with a protecting coating, such as vitreous enamel.

Of the various means heretofore employed for attaching feet to such articles, the most satisfactory and desirable, as to simplicity 20 and effectiveness in structure and operation, has been to provide the outer surface of a tub with lugs adapted to form a tapered dove-tail slot, and to provide as an integral part of the foot a tapered or wedge-shaped 25 tongue adapted to be engaged by the lugs formed upon the tub. When attaching the foot to the tub, the tongue has been driven between the lugs so as to be firmly engaged thereby, and, in order to diminish the liability 30 of the foot becoming loose and ultimately falling off, a stud bolt has been inserted through the tongue, the inner end of such bolt being engaged by an abutment suitably formed upon the surface of the 35 tub. This foot attaching means has been found to be objectionable, first because the stress upon the lugs caused by driving the tongue into secure position is liable to injure the enamel on the inner surface of the 40 tub; secondly, when the tongue is not securely driven into position, the foot is liable to become loose and rattle or fall off; and finally, both the tub and foot being formed of unmachined cast iron the surface of 45 which is necessarily irregular, it is practically impossible to so position with relation to the lugs the stud-bolt engaging-lug upon the surface of the tub that a neat fit will be obtained in all cases without more 50 or less driving the tongue between the lugs.

The object of my invention therefore is to provide a means for securing the tongue of a foot to the lugs of such articles, which

means will be effective to firmly hold the foot in its proper position regardless of the 55 irregular surface of the contacting members and without exerting excessive and enamel-injuring stress upon the lugs.

In the accompanying drawing, which forms part of my specification, I have illustrated an embodiment of my invention.

Figure 1 of the drawing is a sectional view of a portion of a tub with a foot secured thereto, such section being taken on the line I—I, Fig. 2; Fig. 2 is a bottom plan 65 view of the disclosure of Fig. 1, the supporting foot being shown in the section plane indicated by the line II—II, Fig. 1; and Fig. 3 is a sectional view taken on the line III—III, Fig. 2.

In the several figures like numerals are used to designate like parts.

Referring to the drawing, the outer surface of a tub body 1 is shown provided with beveled lugs 2, 2^a, forming a dove-tail slot 75 between them so tapered as to receive the beveled wedge-shaped tongue 3 formed integrally with the foot 4. The means which I preferably employ for firmly holding the tongue 3 between the lugs 2, 2^a, without exerting excessive stress upon such lugs, consist of an auxiliary stop 5 adapted to be secured to the tongue 3 and to abut against the ends of the lugs 2, 2^a. Such stop may be secured to the tongue 3 by means of a stud-bolt 8 extending into a screw-threaded hole in such tongue, and the portions of the stop abutting against the lugs 2, 2^a preferably consist of wings 6, 6^a, the lug-abutting ends of which are preferably beveled, as shown, 80 to correspond with the bevel on said lugs. It will be readily understood that the irregularities of the contacting surfaces of lugs and tongue will cause a variation in the length of the tongue 3 extending beyond 85 the inner end of the lugs 2, 2^a. To the end that the stop 5 may be adjusted to compensate for such variation, a slot 7 is formed therein and the bolt 8 extends through such slot. As will be readily seen the thickness 90 of the wall of the stop adjacent to such slot 7 diminishes from the front to rear of the slot, that is, from the end adjacent to the leg to the opposite end. By so beveling or tapering the stud-bolt engaging surface, 100 the tightening of the bolt becomes effective 105

to draw the tongue 3 firmly within the slot formed by the lugs 2, 2^a.

In securing a foot to a tub body by means of my improved stop, the tongue 3 may be inserted between the lugs 2, 2^a to such an extent as may be necessary in order to obtain a neat fit, but without driving the tongue therein. The stop 5 may then be clamped to the end of the tongue 3, the position of the stud bolt 8 within the slot 7 varying according to the length of the tongue extending beyond the inner ends of said lugs. In tightening the stud bolt 8 it will be seen that the beveled ends of the wings 6 and 6^a, as well as the beveled outer surface of the stop, will tend to draw the tongue 3 firmly within the dove-tail slot or groove formed between the lugs 2, 2^a.

I do not wish to limit myself to the details of construction shown herein for obviously many changes may be made by those skilled in the art without departing from the spirit of my invention.

I claim as my invention:

1. The combination of a cast-metal article provided on its outer surface with lugs forming a tapered recess, a supporting member provided with a tongue adapted to fit into said recess and to extend beyond the ends of said lugs, a slotted stop element adjustably secured to the end of said tongue and provided with wings abutting against the ends of said lugs, and a securing mem-

ber extending through said slot and engaging said tongue.

2. The combination of a cast-metal article provided on its outer surface with lugs forming a tapered recess, a supporting member provided with a tongue adapted to fit into said recess, a slot-provided stop element adjustably secured to said tongue and having surfaces abutting against the ends of said lugs, and a bolt extending through said slot and engaging said tongue, the stop-abutting ends of said lugs and the lug-engaging surfaces of said stop being beveled, whereby a tightening of said bolt draws said tongue within said recess.

3. The combination of a cast-metal article provided on its outer surface with protrusions forming a tapered recess, a supporting member provided with a tongue adapted to fit into said recess, a slot-providing stop element adjustably secured to said tongue and abutting against said protrusions, and a bolt extending through said slot and engaging said tongue, the thickness of said stop adjacent to said slot diminishing rearwardly of said supporting member.

In testimony whereof I have hereunto set my hand.

WILLIAM C. MCKINNEY.
